UNITED STATES PATENT OFFICE.

ROBBERT E. HOBGOOD, OF DEXTER, MISSISSIPPI.

HARROW.

SPECIFICATION forming part of Letters Patent No. 681,395, dated August 27, 1901.

Application filed July 23, 1900. Serial No. 24,500. (No model.)

To all whom it may concern:

Be it known that I, ROBBERT E. HOBGOOD, a citizen of the United States, residing at Dexter, in the county of Marion and State of Mississippi, have invented certain new and useful Improvements in Harrows; and I do hereby declare the following to be a full, clear, and exact description of the invention, such as will enable others skilled in the art to which it appertains to make and use the same.

My invention relates to improvements in harrows, and is what is known as a "side" harrow.

The main object of my invention is the provision of a harrow which by reason of the movability of its teeth readily adapts itself for harrowing ground preparatory to sowing seeds, for cultivating young corn or cotton, and for clearing the ground in front of a drill.

Another object of my invention is the provision of a side harrow embodying in its construction simplicity, durability, and cheapness, thus producing a very useful and practical harrow.

To attain the desired objects my invention consists of a side harrow embodying novel features of construction and combination of parts, substantially as disclosed herein.

In the drawings, Figure 1 is a perspective view of my complete harrow. Fig. 2 is a cross-section between the frame and one tooth. Fig. 3 is a modified form of frame and tooth connection. Figs. 4 and 5 are detail views of teeth.

Referring by letter to the drawings, A designates the center piece or bar of the frame, said bar being provided with the two vertical openings B, through which are adapted to pass the bolts C, to which are secured the metal arms D and E. A beam F is secured to the bar by means of the bolt which holds the arm D to the bar, and a short bolt G passes through the beam and secures the upper or outer ends of the arms to the beam, said arms acting as braces for the beam. Upon the ends of the beam are secured the clevis and handle, respectively, both of well-known construction. Recesses or slots H are formed in the front surface of the center bar, in which are adapted to fit the upper ends of the teeth

J, which are more securely held in place by means of the front and back plates K and the bolts L, which pass through said plates, teeth, and bar. These teeth are formed with the curved intermediate portion M, terminating in the point N. Secured in the recess in the forward end of the bar or frame is a tooth O, which is provided with a slot P in its lower end, and adapted to be secured in said slot, and consequently to the lower end of the tooth, is the half sweep Q, and secured to the rear recess is a similar tooth carrying a whole sweep R.

From this description, taken in connection with the drawings, it will be seen that I provide a simple, durable, and inexpensive harrow which is very useful and practical.

In Fig. 3 I have shown a frame which dispenses with the rear and front plates, thus making the harrow much lighter in weight and allowing the teeth to be clamped in the frame, as shown.

I claim—

In a side harrow the combination of a beam, a clevis and a handle connected to said beam, said beam being also provided with a pair of openings for reception of bolts intermediate of its length, a center bar secured to the beam by means of the bolt near the handle, and at an angle to the beam, recesses provided in the forward edge of the bar, teeth fitting in said recesses, plates fitting upon the front and rear sides of the bars, said plates being adapted to be clamped tightly against the bar to hold the teeth in said recesses, a brace secured to the upper side of the beam by means of a bolt in the forward opening of the beam and to the under side of the bar, and another brace secured to the under side of the beam by the same bolt and to the under side of the bar by means of the lower ends of the bolt that secures the beam and the bar together.

In testimony whereof I affix my signature in presence of two witnesses.

ROBBERT E. HOBGOOD.

Witnesses:

LAMAR HENINGTON,
L. C. WELLBORN.
